PULSATOR OPERATED PERCUSSIVE DEVICE

Joseph F. Joy, Pittsburgh, Pa., assignor to Joy Manufacturing Company, Pittsburgh, Pa., a corporation of Pennsylvania

Application March 24, 1948, Serial No. 16,775

5 Claims. (Cl. 60—51)

1

My invention relates to percussive devices, and more particularly, but not exclusively, to rock drills of the percussive type. The usual rock drill of industry requires a source of compressed air generally in the form of a receiver, an air compressor and a driving motor for the compressor. The quantity of air required by an air driven rock drill of substantial size is considerable, and the air is usually supplied by a portable compressor, and accordingly the plant investment for a drilling outfit is substantial and the space required is also considerable.

It is an object of my invention to provide an improved percussive device. Another object is to provide an improved rock drill, a drill per se differing, in external dimension, but little from conventional drills, but having operating mechanism of a different type and which can be caused to function with relatively small auxiliary equipment. Another object of my invention is to provide an improved rock drill having pneumatically effected striking motions of its hammer, and having hydraulically operated means for effecting the return motions of the hammer. A further object of my invention is to provide an improved self-rotating rock drill having improved rotating means. A further object of my invention is to provide in an apparatus of the character last mentioned an improved cushioning means for preventing injury to the parts of the drill when the piston thereof is operating without the hammer portion thereof coacting with the drill steel. A further object of my invention is to provide an improved percussive apparatus in which an improved and highly compact arrangement is provided for utilizing a liquid and a trapped body of gaseous fluid for effecting a percussive action. Still another object is to provide an improved hammer tool having improved control means. A further object is to provide an improved hammer drill having improved means for providing fluid for blowing cuttings from the hole being drilled. Another object is to provide an improved percussive motor having improved cushion means. Still another object is to provide an improved drill having improved rotation mechanism. Still another object is to provide an improved means for holding a working element in desired relation to a striking apparatus. Other objects and advantages of my invention will hereinafter more fully appear.

In the accomplishment of the foregoing results in a preferred embodiment of my invention a hammer element desirably has associated with it a piston moving in a chamber in which air is entrapped at one end of the piston, and with

2

respect to an opposed surface of the piston a hydraulic fluid is alternatively supplied and sharply released.

In the accompanying drawings in which two embodiments of my invention are shown for purposes of illustration,

Fig. 1 is an elevational view of a drilling apparatus incorporating the invention in a hand rotated form.

Fig. 2 is a central longitudinal vertical section through the drilling implement proper of Fig. 1.

Fig. 3 is a horizontal section on the plane of the line 3—3 of Fig. 1, with parts omitted.

Fig. 4 is a vertical section on the plane of the line 4—4 of Fig. 3, with parts omitted.

Fig. 5 is a fragmentary sectional view showing a detail of the air filling valve.

Fig. 6 is a view corresponding generally to Fig. 2, showing an embodiment of my invention in its broader aspects in a self-rotating drill.

Fig. 7 is a section on the plane of the line 7—7 of Fig. 6.

Fig. 8 is a transverse section on the plane of the line 8—8 of Fig. 6.

Fig. 9 is a corresponding section, partially broken away, on the plane of the line 9—9 of Fig. 6, and

Fig. 10 is a section on the plane of the line 10—10 of Fig. 6.

Referring first to the embodiment of the invention shown in Figs. 1 to 5, inclusive, it will be observed that a drilling tool generally designated 1 comprises a handle 2, a cylinder 3 and a chuck mechanism 4, and that there is associated with the drilling implement proper and connected with it by a non-elastic flexible conduit 5, a device 6 for alternately supplying and releasing a hydraulic fluid in appropriate volume. The drill 1 is adapted to operate a drill steel 7 carrying a conventional drill bit. The cylinder 3 comprises a barrel portion 8 and a rear head portion 9, the latter shown as having brackets 10 extending up for connection with the handle 2. Within the cylinder there is a reciprocable piston device 11 comprising a striking bar portion 12 and a head 13. The head comprises a spool portion 14 and a follower portion 15 threaded together as at 16 and having a highly effective packing 17, such for example as is shown in my Patent No. 2,417,828, mounted between the spool and the follower. The forward end of the barrel 8 is provided with an enlarged portion 19 which is received in a bore 20 in a casing member 21 which cooperates with another casing member 22 to form a chamber 23 in which there is housed a suitable resilient member 24, which is adapted

30

35

40

45

50

55

yieldingly to maintain a member 25, to which the drill steel 7 is threadedly connected as at 26, in position to receive blows from the piston but to yield as may be necessary under such blows to permit penetration and to absorb shocks. The resilient member is in the form of a dished diaphragm and is composed of rubberlike material or of such material and fabric and has its outer edge clamped between the parts 21 and 22, and its inner portion bonded to the member 25, as shown in Fig. 2. The member 25 contains a chamber 28, at whose forward end there is a slightly raised anvil 29 upon which blows are adapted to be struck by a raised hammer portion or nose portion 30 on a plug 31 threadedly secured in a bore 32 in the front end of the piston member 11. The plug 31 at its forward end is a close fit for the peripheral wall of the bore 28, which extends upwardly to join a somewhat larger bore 33, in which the head of a bushing 34 is received, this bushing being of substantial radial thickness so that there is provided between its forward end and the hammer portion 30 an annular chamber 35 whose volume changes as the hammer piston is reciprocated. Above the sleeve 34 there is arranged a seal 36 of a type likewise disclosed in the patent above referred to, and above this a plate 38 supported on a shoulder 39 in the member 21. The forward end of the portion 19 of the cylinder 8 presses the plate 38 against the shoulder 39; and a threaded annular plug or clamping sleeve 49 cooperating with threads 41 in the upper end of the member 21 clamps the parts together.

The drill steel 7 is hollow, as shown at 42, and a bore 43 extends through the member 25 and is provided with a check valve 44 for permitting downward flow of fluid to and through the drill steel from the chamber 28, but preventing reverse flow. Another check valve 46 is arranged in a chamber 47 formed in a forward end of the striking bar 12 above the threaded plug 31. Passages 48 open through the walls of the member 21 into communication with the space 35, and this space is placed in communication with the check valve 46 through radial passages 50 and longitudinal grooves 51 formed in the forward end of the striking bar. Accordingly, since the check valve 46 controls but cannot block a passage 52 communicating with the chamber 47, it will be understood that as the striking bar moves upward fluid will be supplied into the chamber 28 through the radial passages 48, the longitudinal grooves 51, the radial passages 50, past the check valve 46 and through the passage 52 into the chamber 28, and, on the downward movement of the piston, the check valve 46 then being closed, the air will unseat the check valve 44, and flow through the passage 42 to the hollow drill bit.

Within an annular recess 55 near the forward end of the portion 19 of the cylinder element there is mounted a split annulus 56 of spring steel or the like, adapted to act as a check valve in conjunction with a series of radial passages 57, which passages communicate with an annular supply passage 59 which has a higher constantly open communication, as through radial passages 60, with the cylinder bore below the piston head 13. The purpose of this valve is to permit hydraulic fluid to be supplied, as later explained, to a point below the head of the piston, to lift the same when the ports 60 are covered, and to provide a definite cushion for the forwardly moving piston as soon as the ports 60 are covered by the head 13.

A hydraulic fluid under pressure is adapted to

be supplied to the chamber 59 and to be released from this chamber by means shortly to be described, this under the control of an end seating throttle valve 61, normally seated by a spring 62, and then precluding flow towards the conduit 5 from the annular supply space 59. The throttle valve is adapted to be moved to open position by a rod 62' abutting the same and passing through a suitably packed opening 63 in the member 21 and connected by a link 64 with an operating mechanism 65 which is rotatable with the handle 2 or with a part of the latter. The throttle valve obviously acts as a check valve when not positively held open, but when held open permits fluid to surge in either direction past it.

For the purpose of supplying a liquid under pressure to the space below the piston head 13 to raise the piston, and for effecting a sudden release of the liquid so supplied to permit the air compressed in the space in the cylinder above the piston head to expand and cause the striking of a blow, I have provided the structures shown in elevation in Fig. 1 and in two sections in Figs. 3 and 4. This pulsator pump includes, as shown, an electric driving motor 70 connected by a suitable shaft 71 to one of a pair of intermeshing rotors 72 and 73 journaled as at 74 in a housing 75 having intercommunicating bores 76 in which the two rotors 72 and 73 are respectively rotatable. The rotors are provided with intermeshing teeth 77, and each of the rotors is provided also with a slot or groove 78 of appropriate size and shape, and the rotors are so intermeshed with each other that the slots 78 are adapted to communicate with each other, as shown in Fig. 4, in a predetermined angular relation of the rotors and to form a large free passage between spaces at the opposite sides of the mesh line of the rotors. These slots 78 are but illustrative of various suitable arrangements for permitting back flow of liquid in predetermined rotor positions. The net flow is backward when the slots are functioning. An opening 79, communicating with both rotor chambers at their point of intersection, is suitably connected with the bore of a reservoir 80 which is adapted to store an adequate quantity of oil or other hydraulic fluid, and which is adapted to be placed under any desired initial pneumatic pressure by means of a valved plug 81 to which gaseous fluid under pressure may be supplied from any suitable source. Below the mesh line of the rotors there is provided another opening 83 which communicates with the conduit 5.

The space within the bore of the cylinder 8 above the piston is adapted to be filled, in the illustrative embodiment disclosed, through a check valve controlled filler plug 85, with gaseous fluid at any desired pressure, a pressure sufficient to impart a blow of the requisite force adequately to operate the drilling implement. A pressure from 60 to 100 p. s. i. would be suitable, but these values are not to be taken as limiting, and the values will depend on design features. Other arrangements to exert a yielding forward pressure may evidently be employed instead of this "air spring."

Before describing the mode of operation more in detail, it should be noted that the reservoir 80 is desirably equal in capacity to the displacement of the forward side of the head of the hammer piston, and that the flexible conduit 5 is filled with liquid when the parts are coupled together, so that, regardless of the length (and cubic contents) of this conduit, there will always be an

arrangement in which, when the pulsator pump is running, and if the throttle valve is not manually held open, all of the fluid in the reservoir will be displaced and a corresponding amount of fluid will be forced into the space ahead of the hammer piston head 13, and the throttle valve will act as a check valve to hold the fluid in the cylinder bore. Thus, when the pulsator pump continues to operate, it will not, while the throttle valve is closed, displace fluid, but when the drill runner forces the throttle valve 61 open and holds it open, the pressure per square inch exerted on the liquid ahead of the piston head 13, being greater than the pressure per square inch in the reservoir 80, the liquid will be caused to surge back and forth and cause the drill to operate.

It will be understood, referring to Fig. 4, that as the rotors turn, the left one in a counter-clockwise direction and the right one in a clockwise direction, they will, when direct communication between the openings 79 and 83 is interrupted, take, in the pockets formed between each succeeding pair of teeth 77, a charge of liquid from the reservoir 80, and deliver it to the space 83, and cause liquid to pass from the latter through the conduit 5 and past the throttle valve 61, and through the supply chamber 59 and the radial ports 60, and this liquid will raise the hammer through its action in the annular space between the striking bar 12 and the wall of the cylinder 8; and by appropriately designing the displacement of the teeth and the cubic contents of the annular space mentioned the requisite retractive movement of the hammer may be effected, and the entrapped gaseous fluid in the space above the piston will be further compressed so that upon the release of the hydraulic fluid the piston may be moved down and caused to strike a blow of suitable force upon the anvil surface 29 and actuate the drilling implement 7. When the rotors 72, 73 have turned through a predetermined angle the transverse grooves 18 move into communication with each other and permit the liquid previously employed to raise the piston 11 to escape quickly back towards the reservoir 80 which is under a lower pressure than the pressure which prevails in the cylinder above the piston 11.

The mode of operation of this form of the invention will be clear from what has been said already. The proportions of the parts of the pulsating pump, so to speak, to the rest of the apparatus may be different from those shown, as a precisely dimensioned drawing is not needed, since the actual sizes are of simple computation. The throttle being manually opened by rotation of the handle 2, and the motor 10 being in operation and driving the rotors 72, 73 at a high rate of speed, it will be evident that slugs of oil will be periodically forced into the cylinder beneath the piston head to raise the piston, and then be released back through the cooperating slots 18 so that the gaseous fluid above the piston, compressed during upward movement of the piston, may re-expand and force the piston downward to effect the imparting of blows of suitable force and high frequency by the hammer surface 30 on the anvil surface 29. As the piston reciprocates, fluid will be drawn in on its up strokes into the chamber 28 and discharged through the passage 43 on the down strokes of the piston to the bore 42 extending to the lower end of the drilling implement 7. In the event that the drilling implement is not against the

work, it is undesirable that unduly heavy blows be imparted to the surface 29, and this is prevented by the fact that on a slight overtravel of the piston head below the mouths of the openings 60 there will be a very effective cushioning by reason of the presence of the ring check valve 56, which ring will, however, open freely when fluid is supplied to the space 59 to enable the fluid to lift the piston head, which may then be too low for fluid flowing through the passages 55 alone to cause it to be moved upwardly again.

When it is desired to stop drilling, the pulsator pump may be stopped, if desired, but the preferred—because easiest—method will be simply to let the valve 61 close, and, as the liquid will be trapped in the space ahead of the piston head 13 in such volume that the pulsator pump will cease to reciprocate a column of liquid, the hammer will stop.

Figs. 6 to 10 show a hammer motor of the self-rotating type. This is generally designated 98 and differs in a number of characteristics from the structure previously described in detail. It is of the automatically rotated type. It is shown 20 as utilizing a solid steel, with the result that no provision for blowing a hole during drilling is provided. Its purely hammer construction, aside from the fact that the striking bar portion 12' of the piston is solid and has no parts associated with it for use in the pumping of air for supply through the drill steel, is essentially the same as the first form of construction described down to the member 21. This member is connected directly by bolts 91 to a modified chuck housing 25 element 22', which, in a suitable bushing 93, rotatably receives a chuck member 94 having a polygonal opening 95 extending therethrough for receiving the polygonal shank 96 of a suitable tool, for example, an auger element 97. The upper end of the chuck member 94 has a radial shoulder 98 cooperating with the upper end of the sleeve 93 to limit downward movement of the chuck member, while upward movement is substantially prevented by a spring ring 99 sprung 30 into a groove 100 in the inner surface of the chuck housing 22'. Above the shoulder 98 there is fixed, or otherwise suitably secured, a ratchet wheel 101 upon the chuck 94, and this ratchet wheel is adapted to coact with the ring 99 to limit upward chuck movement and to be rotated in steps by mechanism best shown in Fig. 7. In this figure it will be observed that aligned cylinder bores 102 and 103 are formed in the opposite extremities of a cylinder block 104 shown as formed integral with the upper portion of the chuck housing 22'. The cylinder bore 103 is shown smaller than the cylinder bore 102 and is connected at its outer end, by a conduit 106, with a chamber 107 in which the stem 108 of the throttle valve 61' is guided. This stem is longitudinally bored at 109 and has radial passages 110 extending through its walls in such position that when hydraulic fluid is admitted into the chamber 59 fluid will also pass into the space 107 and through the conduit 106 to provide an actuating force for a piston arranged in the cylinder 103. The larger bore 102 is connected at its outer end by a conduit 112 with the space above the piston head 13 in the cylinder 8, so that the pressure which is built up in this space is transmitted through the conduit 112 to the larger cylinder bore 102. Within the housing 104, a piston structure 113 is reciprocably mounted. This comprises a head 114 suitably packed as at 35 115 and movable in the cylinder bore 103, and an-

other larger piston portion 116 suitably packed as at 117 and movable in the larger bore 102. Suitably secured to a connecting portion 118 between the pistons is a pawl member 119 which a spring 120 normally maintains in engagement with the teeth of the ratchet wheel 101. The mode of operation of this arrangement will be obvious from what has been said, if it be borne in mind that a device similar to the device 6 is connected with the conduit 5, and alternately forces slugs of fluid under high pressure to the space 59, and releases them from that space. The fluid admitted to the space 59 effects reciprocation of the hammer piston 11, and also, as above indicated, cooperates in effecting reciprocation of the pawl 119, since a portion of this fluid passes through the conduit 106 to act upon the head 114 and cause the pawl to move to turn the ratchet wheel 101 a predetermined distance when fluid is forced into the chamber 59, the fluid supplied to the bore 103 being vented back, of course, when communication is opened from the chamber 59 back to the reservoir 60. When this communication is opened the pressure in the chamber above the hammer piston is at a maximum, and this pressure, acting through the conduit 112, promptly causes retractive movement of the pawl preparatory to the making of a new working movement by reason of the action of the hydraulic fluid under pressure upon the piston structure 113.

The operation of the invention in the second embodiment thereof needs little independent description. It will be evident that each time a surge of liquid passes the throttle valve 61 on its way to the hammer motor a portion thereof will enter the cylinder 103 and cause the drill bit 97 to make a fractional turn during the period in which the hammer piston is being forced upwards or rearwards in its cylinder. Then when the hammer piston is making its working stroke, the gaseous pressure in the cylinder 102 will return the pawl to a position in which it will be ready for another chuck turning movement.

It will be evident that the displacement of the piston 113 is so small that it will be, practically speaking, without substantial effect on the quantity of liquid utilized, but that its displacement, plus the volume ahead of the head 13 in the rearward position of the latter, will be substantially the same as the cubic contents of the reservoir associated with the pulsator pump. It will be apparent that in both of the illustrative embodiments of the invention there is provided an efficient, high speed hammer motor, that in the first embodiment I have disclosed an improved and simple supply means for hole blowing fluid, that an improved drill rotating means is disclosed in the second illustrative embodiment, that in the first embodiment an improved support for a chuck is provided, and that in both forms illustrated a simple, less space consuming and rugged drilling apparatus is provided.

While there are in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desired to secure by Letters Patent is:

1. In a rock drill, a cylinder, a piston reciprocable in said cylinder and having a striking bar

extending through one end of said cylinder, said cylinder having at the other end thereof an energy storing device, and means for supplying pressure to the first mentioned end of said cylinder to move said piston through a substantial distance to effect the storing of energy in said energy storing device sufficient to cause said striking bar to impart a blow of rock-cutting force to a drill bit and for freely venting pressure from said cylinder to permit the striking of such a blow, including for both functions a single intermittent supply, intermediate release, rotary liquid pump.

2. In a rock drill for actuating a drill bit, a cylinder, a piston reciprocable in said cylinder and having a striking bar extending through one end of said cylinder, said cylinder having at the other end thereof an energy storing device, means for supplying pressure to the first mentioned end of said cylinder and venting pressure therefrom including an intermittent supply, intermediate release fluid pump for alternately causing surges of liquid into said first mentioned end of said cylinder to move said piston to effect storage of energy in said energy storage device sufficient to actuate a drill bit and permitting back flow of liquid freely, and means for controlling communication of said pump with said cylinder including an end seating throttle valve opening toward said cylinder, means for resiliently pressing said throttle valve towards seated position, and means for positively opening said throttle valve.

3. In a fluid actuated hammer motor, the combination comprising relatively reciprocable cylinder and piston elements, one of said elements having a forward striking portion, a gaseous fluid under pressure confined in one end of said cylinder element for continuously urging said element with said striking portion in one direction, and means including a reservoir for a hydraulic fluid under an elevated pressure less than the pressure of said gaseous fluid under pressure and means for intermittently displacing fluid from said reservoir to said cylinder element and permitting its return thereto for intermittently supplying hydraulic fluid to and exhausting hydraulic fluid from the opposite end of said cylinder element to move said element with said striking portion in the opposite direction against the action of said gaseous fluid pressure and compress the latter and to permit its return under the force exerted by said gaseous fluid, said gaseous fluid pressure when said hydraulic fluid is exhausted from said cylinder element effecting movement of said element with said striking portion in said one direction to effect the imparting by said striking portion of a hammer blow.

4. In a percussive device, a cylinder, a piston reciprocable in said cylinder and having a striking bar extending through one end of said cylinder, an energy storing device for yieldingly pressing said piston towards said end of said cylinder, means for supplying hydraulic pressure to said cylinder at said end thereof to effect the storage of energy in said device and to permit its release to permit piston actuation in a blow-striking direction including an intermittent supply, intermediate release fluid pump, an end seating throttle valve seating towards said pump and subjected on its back to the pressure subsisting in said cylinder, means for yieldingly pressing said valve in a seating direction, and means for at will opening the same and holding it open.

5. In a percussive device, a cylinder, a piston reciprocable in said cylinder and having a strik-

ing bar, means for yieldingly pressing said piston in a direction to project its striking bar from said cylinder to cause it to impart a blow to an element upon which it impinges, and an intermittent supply, intermediate release pump for delivering liquid to move said piston in the opposite direction, the displacement of said pump and the volume in said cylinder ahead of the piston therein, when the latter is in normal rearward position, being substantially equal.
